HAIR-WAVING CLIP

Max Haberman, Forest Hills, N. Y.

Application July 2, 1942, Serial No. 449,468

6 Claims. (Cl. 132—31)

This invention relates to improvements in hair clips and more specifically to a clip for holding a coiled tress of hair during the setting period required in the forming of ringlet or sculpture curls in women's hair.

It is the general practice in the art of forming ringlet or sculpture curls for the operator to individually insert at least three hair pins into the spirally wound tress of hair to hold the wound tress during the setting period for producing a wave therein. The insertion of three or more hair pins in a single tress is a tedious and time consuming operation. It is therefore the purpose of this invention to provide a single hair clip which may be applied to the spirally wound tress of hair in lieu of the use of hair pins.

Another feature of the invention is the provision of a hair clip which embraces all of the convolutions of the coiled tress to prevent loosening and accidental unwinding of the coiled tress of hair.

A further feature of the invention resides in a curl clip which may be quickly inserted into position and removed without disturbing the curled tress of hair, and which is inducive of quick drying of the hair.

A still further feature of the invention is to provide a hair waving clip which is simple and inexpensive of construction, strong and durable for long life, and quick and easy to manipulate.

Other features of the invention will become apparent as the following specification is read in conjunction with the accompanying drawing, in which:

Figure 1 is a top plan view of the hair waving clip in position upon a spirally wound tress of hair.

Figure 2 is a front elevational view of the clip per se.

Figure 3 is a side elevational view.

Figure 4 is a bottom plan view.

Figure 5 is an enlarged vertical transverse sectional view on the line 5—5 of Figure 2, the spring clamping jaw being illustrated in open position in dotted lines.

Figure 6 is a vertical sectional view of a modified form of clip.

Figure 7 is a vertical transverse sectional view on the line 7—7 of Figure 6.

Figure 8 is a perspective view of a hair coiling device for use in connection with the hair waving clip.

Referring to the drawing by reference characters, and at present to Figures 1 to 5 inclusive the numeral 10 designates the hair waving clip in its

entirety. The clip 10 includes a fork-shaped base 11 comprising spaced horizontally aligned legs 12—12 and upwardly turned angularly disposed attaching portions 13—13. The base 11 is preferably constructed from a split and bent wire hair pin in which the legs 12—12 are provided with confronting humps and valleys to facilitate the insertion of the base beneath the wave to be formed and adjacent to the scalp of the person whose hair is being waved. The portions 13—13 are connected to the lower end of a thumb pressing member 14 formed from a flat piece of bendable metal. The material from which the member 14 is constructed has its lower portion foldable upon itself to provide attaching eyes 15—15 which respectively receive and tightly grip the respective attaching portions 13—13. The upper portion of the material from which the member 14 is formed is foldable flat upon itself as at 16 to reinforce the same while an intermediate portion of the folded material is bent outwardly at right angle to form opposed ears 17—17 in which the ends of a pivot pin 18 are fixedly mounted by the forming of heads thereon.

Pivotedly mounted upon the pivot pin 18 is a clamp member 19 which includes a ring-like clamping jaw 20, the annular wall of which is concavo-convex in cross section and which wall is provided with closely spaced openings 21 for ventilating purposes and for lightening the weight of the clip as a whole. Integral with the outer rear edge of the jaw 20 are spaced aligned eyes 22—22 through which the pivot pin 18 freely extends. Integral with the eyes 22—22 is an upstanding flat finger piece 23 which is disposed at an angle substantially forty-five degrees from the flat plane of the jaw 20. The intermediate coiled portion 24 of a spring 25 surrounds the pivot pin 18, the terminal legs 26—26 of the spring respectively engaging the rear of the finger piece 23 and the other leg abutting the reinforced front side of the thumb member 14. The spring 25 acts to normally urge the jaw 20 to close position against the legs 12—12 as shown in full lines in Figures 2 to 5 inclusive, but which jaw may be swung to open position as shown in dotted lines in Figure 5 by the thumb and forefinger of the hand of an operator pressing simultaneously upon the thumb member 14 and the finger piece 23.

In use, the tress of hair A such as is shown in Figure 1 is coiled inwardly toward the scalp by the fingers of the operator, such coiling being the practice in preparing the tress of hair for producing what is known by hair dressers as a

ringlet or sculpture curl. The operator holds the coiled tress of hair with one end and with his other hand, he presses upon the member 14 and finger piece 23 to swing the jaw 20 to open position, whereupon the hair pin like base 11 is inserted beneath the convolutions of the coiled tress A so that all of the convolutions thereof lie within the clamping surface of the jaw 20 when the manipulating members 14 and 23 are released. The spring 25 closes the jaw 20 and the entire outer circumferential edge thereof presses upon the convolutions of the coiled tress of hair A and prevents loosening and accidental unwinding of the same. Water and lotions are generally used in the forming of ringlet and sculpture curls, and quick drying of any moisture within the hair gripped by the clip is effected by the air ventilating openings 21. After the coiled tress of hair has set, the operator removes the clip 10, by gripping and pressing upon the manipulating members 14 and 23, whereupon the clip may be freely slid from the hair without disturbing the same.

In Figures 6 and 7 of the drawing, I have shown a modified form of the invention in which clamping distance between the jaw 20 and the hair pin base 11 may be adjusted to accommodate varying thicknesses of coiled hair. In this form the attaching portions 13 of the base 11 are made longer and are connected at their upper ends by bridge portion 27. In addition to the eyes 15, the thumb pressing member 14 is provided with additional eyes 15'-15' which align with the eyes 15-15 to slidably receive the legs 13-13. The bridge piece 27 limits the downward sliding movement of the fork base 11 relative to the clamping jaw 20. These adjustable parts are releasably held in adjusted position by the frictional contact of the legs 26-26 of the spring 25 with the confronting faces of the thumb piece 14 and the finger piece 23. By reason of this adjustment, the clamping jaw 20 may be made to assume a parallel position relative to the base 11 to efficiently clamp the convolutions of the wound tresses of hair of different thicknesses.

In Figure 8 I have illustrated a hair coiling device 30 which may be used in association with the clip 10 in winding a tress of hair A into coiled form. The coiling device 30 comprises a shank 31 having a hair engaging hook 32 formed at one end thereof. The hook 32 extends in a plane at right angle to the axis of the shank. In use, the hook end of the device 30 is inserted through the central opening in the ring-like jaw 20 and is hookingly engaged with the scalp end of the tress of hair A. By imparting a turning movement to the head end 33 of the device 30, the tress will be coiled, and as the coiled hair builds up between the jaw 20 and base 11, the jaw will automatically rise against the tension of the spring 25. The coiled hair is held clamped during the winding operation, and when the entire length of the tress of hair has been wound, the device 30 is withdrawn and the coiled tress is clampingly held by the jaw 20 and base 11.

While I have shown and described what I consider to be the most practical construction of my invention, I wish it to be understood that

such changes as come within the scope of the appended claims may be resorted to if desired.

Having thus described the invention, what I claim as new and desire to secure by Letters Patent of the United States, is:

1. A hair curling clip comprising a fork-like base, a thumb pressing member connected to said base and extending upwardly therefrom, a clamping jaw pivoted to said member and overlying said base, spring means acting upon said jaw to swing the same to closed position toward said base, and a manipulating element fixed to said jaw and extending angularly therefrom, whereby the member and element may be gripped by the thumb and forefinger of the hand of an operator and the element forcibly pressed to swing the jaw to open position to facilitate the sliding of the fork-like base beneath a coiled tress of hair to be waved and whereby subsequent release of the member and element permits the spring means to swing the jaw member to closed position in clamping engagement with the convolutions of the coiled tress of hair.

2. A hair curling clip as set forth in claim 1, in which the clamping jaw comprises a ring which is concavo-convex in cross section.

3. A hair curling clip as set forth in claim 1, in which the clamping jaw comprises a ring having an annular channel in the underside thereof, the walls of the channel having an annular series of spaced openings therein.

4. A hair curling clip comprising a hair pin base, a thumb pressing member connected to said base and extending upwardly therefrom, a pair of spaced opposed ears carried by said member and extending outwardly therefrom over said base, a pivot pin mounted in said ears, a ring-like jaw pivotally mounted on said pivot pin, a manipulating element connected to said jaw and extending upwardly at an angle therefrom, and a spring having a coiled body encircling said pivot pin and also being provided with terminal legs respectively engaging the confronting sides of the thumb pressing member and manipulating element to normally urge the jaw to closed position in the direction of said base.

5. A hair waving clip as set forth in claim 4, in which the thumb pressing member is slidably connected to the base to facilitate adjustment of the jaw relative to the base, said jaw being held in an adjusted position by the frictional engagement of the terminal legs of the spring with the confronting sides of the thumb pressing member and the manipulating element.

6. A hair curler clip for gripping and securing the convolutions of a flatly wound tress of hair comprising a hair pin jaw member, a manipulating element connected to and extending upwardly at an angle from said hair pin jaw member, a ring-shaped jaw member pivotally connected to said manipulating element for cooperative clamping action with said hair pin jaw member, a manipulating element extending upwardly from said ring-shaped jaw member, and spring means acting upon the jaw members to move the same toward each other to closing position.

MAX HABERMAN.
